UNITED STATES PATENT OFFICE.

AUGUSTUS D. KLABER, OF LONDON, ENGLAND, ASSIGNOR TO A. B. DICK COMPANY, OF CHICAGO, ILLINOIS, A CORPORATION OF ILLINOIS.

MEANS FOR ATTACHING STENCIL-SHEETS TO DUPLICATING-MACHINES.

SPECIFICATION forming part of Letters Patent No. 739,498, dated September 22, 1903.

Application filed October 3, 1902. Serial No. 125,783. (No model.)

To all whom it may concern:

Be it known that I, AUGUSTUS D. KLABER, a subject of the King of Great Britain, residing at London, in the county of Middlesex, England, have invented a certain new and useful Improvement in Means for Attaching Stencil-Sheets to Duplicating-Machines, of which the following is a description.

My invention relates to improvements in means for attaching stencil-sheets to duplicating-machines; and my object is to provide a simple, efficient, and cheap device for the purpose.

In the drawings, Figure 1 is a section through a portion of the stencil-carrier of a duplicating-machine of common form with my present improvements thereon, and Fig. 2 a perspective view of the fastening device viewing the same from the under side.

Corresponding parts are represented by the same numerals of reference.

The duplicating-machine, as is common, is provided with the two bars 1, forming a vertical slot between them. One of the bars may be provided with a notch 2 on its inner face. The stencil-sheet 3 is stretched in position over the stencil-carrier and near one end is engaged within the slot between the bars 1 by a locking-plate 4. This locking-plate is struck downward to form a spring-rib 5, which forces the stencil-sheet within the slot. Preferably the spring-rib is provided with offset tongues 6, which engage the recess 2 in one of the bars 1, thereby holding the lock firmly in place. The extension 7 of the lock is curved, as shown, so as to follow the periphery of the stencil-carrier, and acts as a protector for the sheet to receive the impact of the impression-roller in the operation of the machine. When the sheet is to be removed, the extension 7 of the lock is pressed toward the rib 5 to withdraw the tongue 6 from the recess 2, thereby releasing the lock and permitting its ready removal.

The device is very simple and cheap in construction and in addition to effectively holding the stencil-sheet in position also acts as a protector for the sheet from the effect of the impression-roller, as explained.

Having now described my invention, what I claim is—

1. The combination with a stencil-carrier having a slot therein, of a locking-plate having an elastic rib for holding the stencil-sheet in said slot, substantially as set forth. 55

2. The combination with a stencil-carrier having a slot therein, of a locking-plate having an elastic rib for holding the stencil-sheet in said slot, and a tongue on said rib engaging a recess at the side of said slot, substantially as set forth. 60

3. The combination with a stencil-carrier having a slot therein, of a curved plate protecting the stencil-sheet, and an elastic rib on said plate for securing the stencil-sheet in said slot, substantially as set forth. 65

4. The combination with a stencil-carrier having a slot therein, of a curved plate protecting the stencil-sheet, an elastic rib on said plate for securing the stencil-sheet in said slot, and a tongue on said rib engaging a recess at the side of the slot, substantially as set forth. 70

5. As a new manufacture, a locking-plate for stencils comprising a curved extension 75 and an integral elastic rib, substantially as set forth.

6. As a new manufacture, a locking-plate for stencils comprising a curved extension, an integral rib, and a tongue on said rib, substantially as set forth. 80

This specification signed and witnessed this 2d day of October, 1902.

AUGUSTUS D. KLABER.
